(57) **CLAIM**

The ornamental design for a protective tool for a twisted member, as shown and described.

DESCRIPTION

FIG. 1 is a perspective view of a protective tool for a twisted member of an embodiment formed from two half-bodies, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the half-body thereof;

FIG. 9 is a front view of the half-body thereof;

FIG. 10 is a rear view of the half-body thereof;

FIG. 11 is a left side view of the half-body thereof;

FIG. 12 is a right side view of the half-body thereof;

FIG. 13 is a top view of the half-body thereof;

FIG. 14 is a bottom view of the half-body thereof; and,

FIG. 15 is a perspective view thereof shown in an unclaimed environment of use.
